US0D1072847S

(12) **United States Design Patent** (10) **Patent No.:** **US D1,072,847 S**
Caro et al. (45) **Date of Patent:** **** Apr. 29, 2025**

(54) **ELECTRONIC DEVICE WITH GRAPHICAL USER INTERFACE**

(71) Applicant: **Apple Inc.**, Cupertino, CA (US)

(72) Inventors: **Pablo Caro**, San Francisco, CA (US); **Marcel van Os**, Santa Cruz, CA (US)

(73) Assignee: **Apple Inc.**, Cupertino, CA (US)

(**) Term: **15 Years**

(21) Appl. No.: **29/870,835**

(22) Filed: **Feb. 6, 2023**

Related U.S. Application Data

(63) Continuation of application No. 29/735,732, filed on May 22, 2020, now Pat. No. Des. 977,514, which is a continuation of application No. 29/649,893, filed on Jun. 3, 2018, now Pat. No. Des. 885,426.

(57) **CLAIM**

The ornamental design for an electronic device with graphical user interface as shown and described.

DESCRIPTION

FIG. 1 is a front view of a display screen or portion thereof with graphical user interface showing the claimed design; FIG. 2 is another embodiment thereof; and, FIG. 3 is a front view of an electronic device having a display screen with the graphical user interface of FIG. 1 applied to the display screen. The graphical user interface design of FIG. 2 may be similarly applied thereto. The broken lines in the figures show a display screen or portion thereof, or an electronic device having a display screen, and form no part of the claimed design.

1 Claim, 3 Drawing Sheets
